MAGNETICALLY CONTROLLED SWITCH

Harvey Hubbell, Long Hill, Conn.

Application February 3, 1945, Serial No. 575,959

9 Claims. (Cl. 209—87)

1

This invention relates to electrical switches, and has for an object to provide a magnetically operated switch of improved construction and arrangement which may be constructed either as a sealed or unsealed switch, the sealed switch having contacts enclosed in a sealed chamber so that it may be used in atmospheres where there might be fumes or explosive gases, and there is no danger of the arcing incident to make and break of the circuit igniting adjacent objects.

Another object is to provide a switch construction in which the movable switch element and co-operating contacts may be enclosed in a sealed chamber with the control means for the switch located outside this chamber.

A further object is to provide a switch construction in which the movable switch contact is mounted on and movable with a permanent free-floating magnet which is operated to shift the movable contact toward and from the stationary contact by means of another permanent magnet mounted so as to be shifted relative to the first magnet to shift the first magnet in opposite directions depending on the position of the second magnet.

With the foregoing and other objects in view I have devised the construction illustrated in the accompanying drawing forming a part of this specification. It is, however, to be understood the device is not limited to the specific details of construction and arrangement shown but may embody various changes and modifications within the scope of the invention.

In these drawings:

Fig. 1 is a longitudinal section through the switch showing the movable contact in the circuit closing position;

Figs. 2 and 3 are transverse sections substantially on lines 2—2 and 3—3 respectively of Fig. 1;

Fig. 4 is a top plan view with the operating knob removed, and

Fig. 5 is a section similar to Fig. 1 but showing the parts in the position they occupy with the switch in the open circuit position.

In the construction shown by way of illustration the device comprises a body 10 of glass or other suitable molded plastic insulating material, and this may be provided with a sealed chamber 11 in which is mounted the movable contacts 12 adapted to engage and bridge spaced stationary contacts 13 forming the terminals of conductor elements 14 sealed in the glass or other insulating material, and provided outside the body with means for connecting the conductor leads to the conductors 14, such, for example, as the binding screws 15. The movable contacts 12 may form

the end portions of a conductor strip 16 of good conducting metal, such, for example, as phosphor bronze, and the contacts may be in the form of round or semicircular bumps struck up from the flat strip. It is mounted on a permanent movable magnet 17. It may be secured to this magnet in any suitable way, but in the form shown is provided with ears 18 extending upwardly from its lateral side edges on opposite sides of the magnet 17 and folded over the top thereof. This magnet is preferably a rectangular straight bar substantially as shown, and is preferably made of some of the newer ferrous alloys which will retain a high degree of magnetism for an indefinite period, such for example as "alnico."

The chamber 11 in which this bar magnet and the contacts are mounted is substantially rectangular in cross section, as shown in Fig. 3, so that the magnet is held against turning in the plane of the magnet but may move up and down or laterally to the plane of the magnet toward and from the stationary contacts 13, as shown in Figs. 1 and 5. This magnet is therefore a free-floating magnet and is not attached to any mounting. When in its lower position as shown in Fig. 1, movable contacts 12 engage the stationary contacts 13 and through the connecting strip 16 bridge the stationary contacts and close the circuit. By bending the ends of the strip 16 as shown at 19, the contacts 12 are yieldingly mounted through the resilient action of the strip 16, preventing hammer blows on the contacts 13, and it will be seen from Fig. 5 that when the magnet 17 and the contacts 12 are raised to their upper position against the top wall 20 of the chamber, these contacts 12 are separated from the stationary contacts 13 and the circuit is open.

The free-floating magnet 17 is shifted to and held in its different position by a movable magnet 21, and preferably this is a rectangular permanent bar magnet similar to the magnet 17. It is mounted in a recess 22 in the top of the wall 20 on the opposite side of this wall from the magnet 17 and thus may be turned in the plane of the magnet. Any suitable means may be provided for mounting this magnet and turning it, but as an illustration it is enclosed in a metal housing 23 embracing the upper portion of the body 10 and secured thereto by folding the lower end portion 24 about an annular bead 25 on the body. This housing includes a top wall 26 spaced above the top wall 20 of the body and carrying a bearing sleeve or nipple 27 for a rotatable shaft 28 secured at its lower end to the operating magnet 21.

It may be rotated by any suitable means, such for example as a hand knob 28, which is preferably made of insulating material, such, for example, as "bakelite." Mounted between the top wall 26 and the magnet 21 is a spring 30 which comprises a substantially U-shape inverted body portion 31 seated on and embracing the magnet 21 so as to turn with it and the shaft 28, and having upward and outwardly inclined spring arms 32 provided with laterally curved end portions or feet 33 running on an inwardly extending circular bead 34 formed in the top wall 26. This bead is provided with recesses or gaps 35 (Fig. 4) into which the feet 33 may seat when the control or operating magnet 21 is in alignment with the operated or floating magnet 17 to yieldingly hold this magnet 21 in this position, but will slide out of these recesses when the shaft 28 and magnet 21 are rotated by the knob 28.

It will be seen when the parts are in the position of Fig. 1 with the magnet 21 lying in alignment with the magnet 17 and with the north and south poles of this magnet adjacent the north and south poles respectively of the movable magnet 17, that these poles will repel each other and shift the floating magnet 17 downwardly or away from the magnet 21 and the top wall 26 of the chamber, carrying the contacts 12 into engagement with the contacts 13 to close the circuit. This action between the magnets will also hold the magnet 17 and the movable contacts in this position. If now the upper magnet 21 is rotated 180 degrees or a half revolution in the plane of the magnet to the position of Fig. 5, the north and south poles of the magnet 21 will be in alignment with and adjacent the south and north poles respectively, or that is, the poles of opposite polarity, of the floating magnet 17. The poles of the upper magnet will therefore attract the lower magnet, lifting it to its upper position against the top wall 26 of the chamber, as shown in Fig. 5, carrying the contacts 12 away from the contacts 13 opening the circuit, and this coaction of the magnets will retain the magnet 17 and the movable contacts in this position. It will therefore be seen the magnet 17 is positively shifted in opposite directions by the magnet 21, through alternate attraction and repulsion between the two magnets, depending on the position of magnet 21 and its poles in relation to the poles of magnet 17, and will be retained in its different positions by the reactions between the magnets. There is, however, no mechanical connection between the two, and if desired, the floating magnet 17 may be enclosed in a sealed chamber, although of course it may be operated in an open or unsealed chamber if desired. Also the operating magnet 21 may be located outside the sealed chamber and operates the movable magnet through a separating wall of nonmagnetic material.

This makes a very simple construction involving a minimum number of parts, and one which will operate effectively indefinitely. The movable magnet and therefore the mounting for the movable contact is positively operated in both directions by the control magnet without the use of springs and similar return devices, and therefore there are no springs to become fatigued or break. Furthermore, the movable contact will be operated in a quick make and break action, because when the control magnet 21 is rotated from the position of Fig. 1, the lower magnet is held in its lower position, or the circuit closing position, until the upper magnet is turned sufficiently to bring its poles adjacent the respective poles of

opposite polarity of the lower magnet, when it will be quickly shifted to its upper position giving a quick break of the contacts. Similarly, when the upper or control magnet is rotated from the position of Fig. 5 to the position of Fig. 1, the lower magnet is held in the upper position until the upper magnet is turned sufficiently to overcome the attraction between the two magnets and then the repulsion between them will quickly shift it to its lower position.

In some cases the member 17, instead of being a permanent magnet could be a member of magnetic material such as soft iron or the like. In such a case it would be attracted by the control magnet 21 in either of its two positions of Figs. 1 and 2 to shift the member 17 and the switch contacts 12 upwardly. However, when magnet 21 is in an intermediate position at right angles to the member 17, it would not have sufficient attraction to shift members 17 and 12 upwardly and they would drop to their lower position by force of gravity if the device is used in the upright position shown in Figs. 1 and 5, or a spring could be used to shift them to the closed position. Or the members could be reversed, so that the control member 21 is not a permanent magnet but made of some magnetic material such as soft iron or the like, and the free floating member 17 could be a permanent magnet so that it would be attracted to member 21 when the two members are in alignment or parallel relation. It is, however, preferred that both members 17 and 21 be permanent magnets.

Having thus set forth the nature of my invention what I claim is:

1. An electric switch comprising a free floating permanent magnet, means guiding said magnet for lateral movements while holding it against turning movements in the plane of the magnet, a stationary contact, a second contact carried by the magnet and movable therewith to and from the first contact, and a second magnet substantially parallel to the first magnet and mounted for turning movements about an axis at right angles to the planes of the magnets whereby like and unlike poles of the two magnets may be brought adjacent each other to shift the first magnet in opposite directions by mutual repulsion and attraction between adjacent poles of the two magnets.

2. An electric switch comprising a free floating permanent bar magnet, means guiding said magnet for movements lateral to the plane of the magnet while holding it against turning in said plane, a stationary contact, a second contact carried by the magnet and shifted to and from the first contact by movements of the magnet, and a second permanent bar magnet mounted adjacent the first magnet in a plane substantially parallel to that of the first magnet and rotatable in its plane to bring its poles alternately adjacent the unlike and like poles of the first magnet to shift it toward and from the second magnet by mutual attraction and repulsion between the adjacent poles of the two magnets.

3. An electric switch comprising a free floating permanent bar magnet, an electric contact carried thereby, a body of insulating material providing a sealed chamber for the magnet and contact, a stationary contact in the chamber, said chamber being noncircular so as to guide the magnet for movement toward and from the stationary contact while holding the magnet against turning movements in the plane of the magnet,

a second permanent magnet mounted outside the chamber adjacent the first magnet, and means for mounting the second magnet for movements to bring its poles alternately adjacent similar and opposite poles of the first magnet to shift it and the movable contact toward and from the stationary contact by mutual repulsion and attraction between adjacent poles of the two magnets.

4. An electric switch comprising cooperating stationary and movable contacts, a pair of permanent bar magnets arranged in adjacent substantially parallel planes and with their centers in substantial alignment so that both poles of each magnet are adjacent the respective poles of the other magnet, means connecting one of said magnets with the movable contact to operate it, means for guiding the latter magnet for bodily movement toward and from the other magnet while holding it against turning in the plane of the movable magnet, and means for turning the other magnet in the plane of this magnet to bring both its poles alternately and simultaneously adjacent like and unlike poles of the shiftable magnet so that mutual repulsion and attraction between adjacent poles of the two magnets may act to shift this latter magnet in opposite directions and shift the movable contact.

5. An electric switch comprising a body member of insulating material enclosing a chamber, cooperating stationary and movable contacts in said chamber, a permanent bar magnet in said chamber connected with the movable contact, means for guiding said magnet for bodily lateral movement while holding it against turning movement in the plane of the magnet, a control magnet at the opposite side of one wall of the chamber with both its poles adjacent the respective poles of the first magnet, and means for shifting the control magnet to bring both its poles alternately and simultaneously adjacent like and unlike poles of the first magnet whereby the mutual repulsion and attraction between adjacent poles of the magnets will shift the first magnet in opposite directions.

6. An electric switch comprising a body member of insulating material enclosing a chamber, cooperating stationary and movable contacts in said chamber, a permanent bar magnet in the chamber connected with the movable contact, said chamber being noncircular in cross section so as to guide said magnet for lateral movement longitudinally of the chamber while holding it against rotative movement in the plane of the bar, a second permanent bar magnet mounted at the outer side of the end wall of the chamber and substantially parallel to the first magnet, and means for turning the second magnet in the plane of this magnet to bring its poles alternately adjacent like and unlike poles of the first magnet so that the mutual repulsion and attraction between adjacent poles of the magnets will shift the first magnet in opposite directions in the chamber.

7. An electric switch comprising a body member of insulating material enclosing a chamber, cooperating stationary and movable contacts in said chamber, a free floating permanent bar magnet in said chamber and connected with the movable contact for operating it, said chamber being noncircular in cross section and adapted to guide the magnet for lateral movements while holding

it against turning movements in the plane of the magnet, a casing enclosing one end of the body, a second permanent bar magnet mounted in the casing adjacent the outer side of an end wall of the body and substantially parallel with the first magnet, a shaft mounted in the casing and connected with the second magnet, means for turning the shaft to turn the second magnet in the plane of this magnet to bring it into substantial alignment with the first magnet with its poles alternately adjacent like and unlike poles of the first magnet to shift this latter magnet in opposite directions in the chamber by the mutual repulsion and attraction between adjacent poles of the magnets, a spring member mounted between the second magnet and the casing and provided with spring arms, and means cooperating with these arms to retain the second magnet in substantial alignment with the first magnet.

8. An electric switch comprising coacting movable and stationary contacts, a pair of permanent bar magnets mounted in adjacent laterally spaced substantially parallel relation, means connecting one of said magnets with the movable contact for operating it, means guiding said latter magnet for lateral movement while holding it against turning movements in the plane of this magnet, and means for turning the other magnet in the plane of this magnet to bring its poles alternately adjacent like and unlike poles of the first magnet to shift this latter magnet from and toward the other magnet by the mutual repulsion and attraction between the adjacent poles of the magnets.

9. An electric switch comprising a body member of insulating material enclosing a chamber, cooperating stationary and movable contacts in said chamber, a free floating permanent bar magnet in said chamber and connected with the movable contact for operating it, said chamber being noncircular in cross section and adapted to guide the magnet for lateral movements while holding it against turning movements in the plane of the magnet, a second permanent bar magnet mounted adjacent the outer side of an end wall of the body and substantially parallel with the first magnet, and means for turning the second magnet in the plane of this magnet to bring it into substantial alignment with the first magnet with its poles alternately adjacent like and unlike poles of the first magnet to shift this latter magnet in opposite directions in the chamber by mutual repulsion and attraction between adjacent poles of the two magnets.
